(57) **CLAIM**

The ornamental design for a tire valve, as shown and described.

DESCRIPTION

FIG. 1 is a side elevational view of a tire valve showing our original design;

FIG. 2 is a top plan view thereof;

FIG. 3 is a bottom plan view thereof; and,

FIG. 4 is a perspective view thereof.

In the drawings, the broken lines are for illustrative purposes only and form no part of the claimed design.
